Primary Examiner — Philip S Hyder(74) *Attorney, Agent, or Firm* — Oliff PLC(57) **CLAIM**

The ornamental design for an ice axe, as shown and described.

DESCRIPTION

FIG. 1 is a front, left-side perspective view of the ice axe;

FIG. 2 is a left-side elevational view thereof;

FIG. 3 is a top plan view thereof;

FIG. 4 is a rear elevational view thereof;

FIG. 5 is a front elevational view thereof;

FIG. 6 is a right-side elevational view thereof;

FIG. 7 is a bottom plan view thereof; and,

FIG. 8 is a rear, right-side, top perspective view thereof.

The broken lines depict portions of the ice axe that form no part of the claimed design.
